US00D914731S

(12) **United States Design Patent** (10) **Patent No.:** **US D914,731 S**
Fischbach (45) **Date of Patent:** **** Mar. 30, 2021**

(54) **DISPLAY SCREEN OR PORTION THEREOF WITH GRAPHICAL USER INTERFACE**

(71) Applicant: **Siemens Schweiz AG**, Zürich (CH)

(72) Inventor: **André Fischbach**, Steinhausen (CH)

(73) Assignee: **SIEMENS SCHWEIZ AG**, Zurich (CH)

(**) Term: **15 Years**

(21) Appl. No.: **29/736,953**

(22) Filed: **Jun. 4, 2020**

Related U.S. Application Data

(62) Division of application No. 35/504,879, filed on Nov. 9, 2017 (U.S. filing date under 35 U.S.C. 384), and having an international filing date of Nov. 9, 2017, now Pat. No. Des. 887,437.

(57) **CLAIM**

The ornamental design for a display screen or portion thereof with graphical user interface, as shown and described.

DESCRIPTION

The FIGURE is a display screen or portion thereof with graphical user interface.

The broken lines showing an electronic device are included to illustrate environmental structure; the broken lines showing portions of the graphical user interface are included to illustrate portions of the article; all broken lines form no part of the claimed design.

1 Claim, 1 Drawing Sheet
